UNITED STATES PATENT OFFICE.

JOSEPH T. TILLMAN AND PHILIP SCHWEICH, OF MINNEAPOLIS, MINNESOTA.

DEVICE FOR APPLYING, REMOVING AND SEALING JAR COVERS OF MASON JARS.

1,407,710.

Specification of Letters Patent. Patented Feb. 28, 1922.

Application filed March 5, 1921. Serial No. 450,065.

To all whom it may concern:

Be it known that we, JOSEPH T. TILLMAN and PHILIP SCHWEICH, citizens of the United States, residing at Minneapolis, in the county 5 of Hennepin and State of Minnesota, have invented certain new and useful Improvements in Devices for Applying, Removing and Sealing Covers of Mason Jars; and we do hereby declare the following to be a 10 full, clear, and exact description of the invention, such as will enable others skilled in the art to which it appertains to make and use the same.

Our invention provides an extremely 15 simple and highly efficient device for applying, removing and sealing covers of Mason jars, and, generally stated, the invention consists of the novel construction and combinations of parts hereinafter described and defined in the claims.

The device comprises two levers or handle members pivotally connected and formed with approximately semi-circular cover-clamping segments between their handle 25 ends and pivot. One of the clamping segments is formed with a depending lug or ear to which a sealing roll is journaled. This roll is so positioned that when the clamping segment is applied to the upper 30 portion of the jar cover, it, said roll, will engage and run over the edge flange of the cover and press or iron out the same so that even if distorted or rough, said edge flange will be made smooth and form a tight or 35 sealed joint with the rubber gasket or ring customarily employed.

In the accompanying drawings, which illustrate the invention, like characters indicate like parts throughout the several 40 views.

Referring to the drawings:

Fig. 1 is a perspective showing the device applied to the cover of a Mason jar;

Fig. 2 is a section on the line 2—2 of 45 Fig. 1; and

Fig. 3 is an enlarged section approximately on the line 3—3 of Fig. 1.

The numeral 4 indicates a Mason jar, the 50 numeral 5 the jar cover and the numeral 6 the rubber gasket or ring. As is well known, the edge flange 5^a, of the cover, is frequently distorted or bent by one cause or another, but usually by the use of a knife or the like in loosening the cover from a jar to which 55 it has previously been applied.

The clamping levers 7 are formed with segmental approximately semi-circular clamping segments 8 and overlapped ends pivoted at 9. The inner edges of the clamping segments 8 are of such curvature that they will tightly clamp the threadless upper portion of the jar cover when the handle ends of the levers are forced quite close together. One of the clamping segments 8 is integrally formed with a depending obliquely bent ear 10, to the inner face of which a small sealing roll 11 is journaled by means of a stud 12. The face of the roll 11 is preferably conical, so that it will engage the edge flange 5^a of the cover, as shown 70 in Fig. 2, when the tool is applied to the cover. When the tool is applied to the cover as shown and the handle ends of the levers 7 are pressed together with considerable force, the jar cover will be held firmly by 75 the clamping segments, considerably assisted by the action of the roll 11, and the cover can then be turned either on or off with very great force. When the cover has been tightly screwed onto the jar and the jar cover then 80 lightly clamped, the tool can be rotated around the cover, causing the roll 11 to travel over the edge flange 5^a and iron or press out any irregularities in said flange, thereby tightly sealing the jar. 85

To enable the lever members to be made of quite light or thin sheet metal, they are preferably stamped with edge flanges 7^a that run nearly or quite from their pivotally connected ends to their free ends. One of 90 these flanges 7^a is formed as a continuation of the ear 10, or otherwise stated, said ear is formed as a projection of one of said flanges.

What we claim is:

1. A device for applying, removing and sealing Mason jar covers comprising a pair of levers pivotally connected at one end and provided, adjacent their pivoted ends, with cover-clamping segments, one of said segments having a depending ear out of line of the levers and a roll journaled thereto and positioned to engage the edge flange of the jar cover when said clamping segments are applied to the top portion of said cover, said ear being obliquely set and said roll having a conical periphery. 100

2. A device for applying, removing and sealing Mason jar covers comprising a pair of levers pivotally connected at one end and 110

provided, adjacent their pivoted ends, with cover-clamping segments, one of said segments having a depending ear and a roll journaled thereto and positioned to engage the edge flange of the jar cover when said clamping segments are applied to the top portion of said cover, said levers having marginal reinforcing flanges, from one of

which said ear projects, said levers, flanges and ear being integrally stamped sheet metal 10 structures.

In testimony whereof we affix our signatures.

JOSEPH T. TILLMAN.
PHILIP SCHWEICH.
